[57] CLAIM

The ornamental design for a ceiling fan dust collector cover for blades, as shown and described.

DESCRIPTION

FIG. 1 is a front elevational view of a ceiling fan dust collector cover for blades showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a perspective view thereof, on a reduced scale, shown in use.

The broken-line showing of a ceiling fan, in FIG. 7, is for illustrative purposes only and forms no part of the claimed design. The pattern on the upper and lower horizontal strips in FIG. 2, is understood to represent an adhesive.
